LAURENCE HERBERT PEARSON AND CLAUDE MARSHALL, OF NOTTINGHAM, ENGLAND

ELECTRICAL REPRODUCTION OF SOUND FROM RECORDS

Application filed February 12, 1930. Serial No. 427,764.

This invention comprises improvements in or relating to electrical reproduction of sound from records and has reference to apparatus for use in the electrical transmission of music, speech and other sounds from gramophone records.

In connection with apparatus of this class an electrical device known as a pick up or collector is employed, adapted for attachment to the tone arm of a gramophone and embodying a metal reed resiliently or pivotally mounted or suspended so as to be capable of a limited oscillatory movement between the poles of an electromagnet. Detachably carried by the reed is a needle adapted to coact with the gramophone records in the known manner so that the vibration set up in said needle and reed by the irregularities in the record surface induce in the pole coils of the magnet varying electric impulses which are suitably amplified and conveyed to a loud speaker such as is used with wireless receiving instruments, or other reproducing instrument.

In order faithfully to reproduce the music, speech or the like in the loud speaker and prevent distortion it is essential that the reed and needle be normally held from uncontrolled movement while permitting the oscillatory motion effected by the record, and to this end it is the custom to damp the lateral motion of said reed and needle between adjustable resilient damping elements or cushions.

The present invention has reference to the type of pick up comprising a permanent magnet of the horseshoe type having coil carrying pole tips associated with each limb and having a metal reed resiliently mounted at its upper part and positioned between said pole tips and adapted to be oscillated to a limited extent by the needle traversing the grooves of the gramophone record to induce electric currents in the coils of the magnet, as previously described.

According to the present invention a pick up or collector is provided embodying in combination a permanent horseshoe magnet, a coil on each pole piece or tip of said magnet, a resiliently mounted metal reed

between said pole coils, the length of said reed approximating the diameter of the pole coils, adjustable reed damping means extending through the pole tips and means for adjustably locking said damping means in position relatively to the reed.

A further feature consists in mounting the pick-up upon a hinged or pivoted tone arm which is provided with counter balancing means, the balance of the tone arm being advantageously adjustable.

For the purpose of more fully describing the nature of this invention reference will now be made to the accompanying drawings, wherein:—

Figure 1 shows in part sectional elevation a pick-up or collector in accordance with this invention.

Figure 2 is a rear view of the device shown in Figure 1.

Figure 3 is a part sectional side elevation of a modified construction of pick-up mounted upon a counter balanced tone arm, said arm having associated therewith means for adjusting the balance thereof.

Figure 4 is an enlarged sectional elevation of a modified construction of pick-up shown in Figure 3.

Figure 5 is a front view looking in the direction of arrow X in Figure 4.

In one method of carrying out the invention the pick up or collector comprises a permanent magnet 1 of horseshoe formation having coils 2 wound on pole tips 1a one of which projects inwardly from each limb of the magnet. On an insulating bar 3 extending across the magnet are a pair of terminals 4 for the coil windings, and the induced currents from said terminals are suitably amplified and conveyed to a suitable reproducing instrument such as a loud speaker. A split metal socket 5 is provided at the one side of the device for attachment to the tone arm of a gramophone.

Depending between the pole tips 1a is a metal reed 7, preferably of rectangular cross section, suitably anchored to a member 6. This member 6 is rigidly connected by a screw 6a and nut 6b to a back plate 1b which may be screwed to the rear of the magnet 1.

and shaped at its upper edge to conform to the curvature of the said magnet. Advantageously the fixing of the reed is approximately midway in the height of the magnet.

5. The reed is bored vertically at its lower or free end to receive a gramophone needle 8, which latter is detachably fixed in position so as to project downwardly by a screw 9 inserted laterally into a threaded hole in the reed.

10. The needle fixing screw 9 is preferably a thumb screw and the length of same is such that the screw head projects out clear of the magnet coils 2 and can be manipulated with ease by the fingers without touching the coils.

15. The pole tips 1a upon which the magnet coils 2 are mounted are of tubular formation and each may be adjustably fixed in position by a screw 10 which is inserted through a 20 plain hole in the magnet end portions 1c and into an internally threaded part of the bore of the pole piece. Each pole tip projects inwardly beyond the coil 2 and the innermost half or part of the bore is preferably of increased diameter so as to accommodate a 25 loose metal piece 11 and a small piece of rubber 12 or equivalent non-conductive resilient material.

30. This rubber element 12 projects a little way beyond the inner face of pole piece 1a, and it will be appreciated that the two rubber elements located one on each side of the reed 7 constitute dampers functioning normally to hold said reed centrally between the 35 magnet poles and preventing promiscuous lateral movement of the reed.

30. The aforesaid screws 10 are hollow, and within each of said screws is a further screw 13 bearing at its inner end on the loose 40 metal piece 11. The axial adjustment of this inner screw 13 effects an adjustment of the said loose piece 11 and damper 12, and also determines the degree of pressure exerted by said damper on the reed.

45. The screw 13 is locked in its adjusted position by nut 14.

50. The dampers being located substantially near to the fulcrum of the reed provides for a maximum amount of leverage of the associated reed and needle and ensures a particularly sensitive operation thereof when operating upon a gramophone record, thus producing exceptionally accurate and clearly defined results in the loud speaker.

55. In a modified arrangement illustrated in Figures 3 to 5 the horseshoe magnet 1 is mounted upon a back plate 15 which has cast integrally therewith a boss 16 by which the pick up is suitably connected to the tone arm 17.

60. In this arrangement the pole pieces 1a instead of being connected directly to the limbs of the magnet 1, are mounted upon angle bracket members 18 which are fixed to the rear plate 15 so that one flange of each angle

member projects outwardly and forwardly from said rear plate. The two limbs of the magnet bear upon the upstanding flanges of the angle members 18, said magnet being secured in position by an insulated or non-magnetic cross bar 3 which extends across the front of the magnet and is connected to the rear plate 15 by a screw, bolt or the like 70 19. The screw member 19 which is located centrally in the width of the pick up also 75 serves as a means for connecting the reed 7, said reed advantageously depending from a member 20 which also functions as a spacing sleeve between the bar 3 and back plate 15. On the plate 15 is also suitably fixed an insulating block or member 21 carrying a pair of terminals 22 to which wire extends from the two coil windings 2 mounted on the pole pieces of the magnet. 80

85. Damping means for the reed are provided as hereinbefore described said damping means being adjustable by screw adjustment also as before-described. In the modified arrangement, however, the screw adjustment for the reed damping means is passed through the upstanding flange of each angle member 18 instead of, as in the first described embodiment, through each limb of the magnet. 90

95. By reason of the fact that the adjustment of the reed damping is effected axially of the pole pieces, the size and weight of the actual reed or armature carrying the needle are reduced to a minimum, and the efficiency of the device consequently enhanced. 100

100. The tone arm 17 is preferably pivoted or hinged to the upper end of a screwed spindle member 23 (Figure 3) said spindle being adapted to rotate within an internally threaded pillar 24, said tone arm having an enlarged portion 25 overhanging a pivot 26 so as to constitute a counter balance for the pick up.

110. Advantageously the overhanging portion 25 of the arm is made hollow and accommodates a weight 27 carried by screw-threaded pin 28 passing through a threaded aperture in the end of said portion 25, the arrangement being such that by rotation of the pin 28 and weight 27 thereon the position of said 115 weight relatively to the pivot 26 can be adjusted and by so doing the balance of the tone arm can be adjusted to the exact required degree. A milled knob 29 is provided at the end of the screwed pin 28 for the manipulation thereof, a fixing nut 30 being advantageously also provided for fixing the weight 27 at the adjusted position. 120

We claim:—

125. 1. A pick up for the electrical reproduction of sound from records, embodying in combination a permanent horseshoe magnet having hollow cylindrical pole pieces, said pole pieces being mounted on bracket members positioned adjacent to the two limbs of 130

the magnet, a coil on each pole piece, a metal reed resiliently suspended between the coils, the length of said reed approximating the diameter of the coils, a screw operating axially within each pole piece, cushion elements for damping the reed located on each side of said reed and said screws functioning adjustably to determine the position of said cushions.

10 2. A pick up for the electrical reproduction of sound from records, embodying in combination a permanent horseshoe magnet, a plate on which said magnet is mounted, said plate being adapted for connection to a tone arm, bracket elements mounted on said rear plate adjacent to the two limbs of the magnet, hollow pole pieces on said brackets, a coil on each pole piece, a reed resiliently suspended between said coils, reed damping cushions, and said cushions being adjustable by screws located and operating axially of said pole pieces and coils.

15 3. A pick up for the electrical reproduction of sound from records, embodying in combination a permanent horseshoe magnet, a rear plate carrying said magnet, said rear plate being connected to a tone arm, an angle bracket fixed to said rear plate adjacent to each pole of the magnet, an externally and internally threaded sleeve screwed through an upstanding part of such bracket, a hollow cylindrical pole piece carried by each sleeve, a coil on each pole piece, a metal reed suspended resiliently between said pole 20 30 35 40 45 50 55 60 65 70 75 80 85 90 95 100 105 110 115 120 125 130
